UNITED STATES PATENT OFFICE

171,470

TILE

Joseph M. Toohey, Affton, Mo.

Application July 11, 1951, Serial No. 15,819

Term of patent 14 years

(Cl. D18—2)

To all whom it may concern:

Be it known that I, Joseph M. Toohey, a citizen of the United States, residing at Affton, in the county of St. Louis and State of Missouri, have invented a new, original, and ornamental Design for Tile, of which the following is a specification, reference being had to the accompanying drawings, forming part thereof.

Fig. 1 is a plan view of a tile according to my design.

Fig. 2 is an edge view thereof.

I claim:

The ornamental design for a tile, substantially as shown.

JOSEPH M. TOOHEY.
